DESIGN FOR A VACUUM CLEANER

Edgar P. Turner, Fanwood, and Charles F. Neagle,
North Plainfield, N. J., assignors to The Singer
Manufacturing Company, Elizabeth, N. J., a
corporation of New Jersey

Application April 8, 1947, Serial No. 138,230

Term of patent 14 years

(Cl. D9—2)

To all whom it may concern:

Be it known that we, Edgar P. Turner and Charles F. Neagle, citizens of the United States, residing respectively at Fanwood, in the county of Union and at North Plainfield, in the county of Somerset and State of New Jersey, have invented a new, original, and ornamental Design for a Vacuum Cleaner, of which the following is a specification, reference being had to the accompanying drawing, forming a part thereof.

In the drawing,

Fig. 1 is a front perspective view of a vacuum cleaner showing our new design, it being understood that the upright portion is to bear surface ornamentation similar to the two small areas indicated thereon and

Fig. 2 is a rear perspective view of the vacuum cleaner shown in Fig. 1.

We claim:

The ornamental design for a vacuum cleaner, substantially as shown and described.

EDGAR P. TURNER.
CHARLES F. NEAGLE.
